UNITED STATES PATENT OFFICE.

JOHN W. ESKHOLME, OF EAST ORANGE, NEW JERSEY, ASSIGNOR TO RED STAR APPLIANCES, INC., OF NEW YORK, N. Y., A CORPORATION OF DELAWARE.

STAMP-CANCELING MACHINE.

Original application filed March 9, 1925, Serial No. 14,045. Divided and this application filed November 17, 1925. Serial No. 69,592.

The present invention relates to machines for handling envelopes, cards, and other flat objects, and is capable of a variety of uses.

5 This application is a division of my pending application, Serial No. 14,045, filed March 9, 1925.

It is an object of the present invention to conveniently provide for the sealing of 10 envelopes.

It is a further object of the invention to provide for printing with ink on a sealed envelope or on a flat card, as for instance to cancel the stamp on an envelope and to 15 print adjacent to the canceled stamp the name of the post office, a date, the hour and the permit number of the user.

It is a further object of the invention to count the number of envelopes, cards, or 20 other flat objects passed through the machine, not for the benefit of the Government in calculating the amount of postage paid thereon, but for the information of the user of the machine.

25 Although the machine is capable of a wide variety of uses, its greatest utility lies in sealing stamped envelopes and then canceling the Government stamp and counting the number of stamps so canceled. Envelopes to be used in this way may be of 30 the character now furnished by the United States Government and having the postage stamp formed directly in the paper of the envelope, or equally well, may be a plain envelope to which an adhesive Government 35 stamp has been affixed.

When the sealed envelopes come from the machine with the stamps canceled, and with the name of the post office and the date 40 printed thereon, they can be delivered in bulk to the post office and there can be distributed directly into the outgoing pouches without the delays and labor incident to first placing them face up on the 45 sorting table and then passing them through the stamp canceling devices now commonly used by the Government employees. In other words, much of the labor now required at the post office is done before the mail 50 reaches the post office with a consequent saving in time in placing the mail in transit to its destination.

The machine of the present invention has a new type of receiving platform on which

the envelopes may be stacked horizontally 55 with their open flaps hanging downward over the side of the platform in shingled relation, means being provided at the side of the stack for keeping the envelopes in proper alignment with a feed roll to which 60 they are to be delivered one by one from the bottom of the stack. The platform also includes an adjustable anti-friction device of 65 novel character adapted by spring pressure to automatically tilt the stack as the number of envelopes in the stack progressively decreases.

The machine also embodies a novel barrier of cylindrical form coacting with the feeding roll and having a slight automatic 70 movement in a direction opposite to that of the feeding roll whereby the wear on the baffle is distributed over its entire cylindrical face.

A moistening device and water fountain 75 of novel construction serves to moisten the downwardly hanging flaps of the envelopes during their passage one by one over the feed roll. Transfer rolls and a coacting inclined guide serve to fold the gummed flap 80 of an envelope upward against the body thereof. The envelope then passes to a pair of sealing rolls where it is firmly squeezed to secure good adhesion of the 85 gummed flap.

When the envelope passes from the sealing rolls it trips a printing mechanism 90 which by its rolling movement over the travelling envelope cancels the postage stamp thereof and prints adjacent to the 95 canceling imprint other vital data, such as the name of the post office, the date, and hour of cancellation. Counting mechanism operatively connected with the printing device records the number of printed imprints and consequently, the number of stamps canceled. The printing mechanism itself is so mounted that it can be swung upward 100 into inverted position to give access to the dies and type with which it is equipped, and the type and dies are so secured in place that their replacement is a matter of but a moment's work, no special tools being required.

Manually controlled levers are provided 105 for throwing the counting mechanism out of action, for throwing the printing roll out of action, and for throwing the inking

roll out of action, when occasion may require, so that if desired, the machine may be operated simply as an envelope sealing machine.

5 Power for the machine is supplied by an electric motor compactly mounted, and those rotating elements of the machine which travel at high speed are equipped with wooden bearing sleeves which are silent in operation, and to which no lubricating oil need be applied by the operator. There is, therefore, no chance that dripping oil will mar or soil envelopes or other articles being passed through the machine.

15 Other details and objects of the complete machine will become clear from the following detailed description taken in conjunction with the accompanying drawings.

Fig. 1 is a side elevation of the complete 20 machine;

Fig. 2 is a sectional plan view of the same on the line 2—2 of Fig. 1;

Fig. 3 is an end elevation of the complete machine as seen from the right of Fig. 1;

25 Fig. 4 is a detail of the anti-friction rollers on the receiving platform;

Fig. 5 is a sectional detail of the water fountain and its valve;

Fig. 6 is a transverse section on the broken 30 line 6—6 of Fig. 1;

Fig. 7 is a fragmentary detail showing the rubber friction surfaces of the main envelope-feeding drum;

Fig. 8 is a fragmentary vertical section on 35 the line 11—11 of Fig. 6;

Fig. 9 is a plan view of the adjustable plates shown at the top of Figs. 6 and 8;

Fig. 10 is a horizontal section on the line 16—16 of Figs. 6 and 8.

40 *Frame work and receiving platform (Figs. 1, 2, 3, 4, 6).*

The frame work of the machine comprises a cast metal base 1 to which is secured, by a 45 plurality of bolts 2, a sub-base 3 integral with which is a vertical supporting plate 4 carrying a hub 5 to serve as a bearing support for certain of the rotating elements. Secured to the vertical plate 4 by bolts 6 50 is a central sheet metal plate 7 on the flanged upper edge of which is bolted a sheet metal platform 8 which extends the entire length of the machine. To its down-turned rear edge (Fig. 6) is bolted a long lower apron 9 55 which extends throughout the length of the machine. On the front down-turned edge of platform 8 is a short lower apron 10 (Figs. 3 and 1) to which is hinged a vertical guide plate 11 (Figs. 1 and 3). At the hinged 60 connection is a coiled spring 12 for controlling the position of guide plate 11.

Above platform 8 and supported by a rear wall 13 bolted thereto is a cover plate 14 which covers the left hand two-thirds of the 65 machine as viewed in Fig. 1, and which

serves as the support for certain adjusting mechanisms. The front edge of cover plate 14 is carried by a front wall plate 15 secured along its lower edge by bolts 16 to a short front apron 17 bolted to the down-turned front edge of platform 8.

The receiving platform for the envelopes to be sealed and then canceled is at the right hand end of the machine as viewed in Fig. 1, and includes a pair of anti-friction rollers 18, 75 the details of which are shown in Figs. 2, 3 and 4.

Platform 8 is provided with a pair of parallel slots 19 (Fig. 2) through which rollers 18 may project to contact with a stack of 80 envelopes horizontally placed thereon. Each roller is mounted to turn freely on a pin 20, the inner end of which is riveted to a vertical leg of a U-shaped support 21. That U-shaped support 21 is carried on the upper 85 end of a pull-rod 22 to the lower end of which is secured a handle 23. This pull-rod is guided by a U-shaped plate 24 secured by bolts 25 (Fig. 4) to a pair of brackets 26, the upper horizontal legs of which contact with the lower face of platform 8 and transversely bridge the parallel slots 19 thereof. To hold this mechanism against free sliding movement along slots 19, there are provided a pair of transverse bars 27 (Fig. 2) through 90 which bolts pass for threaded engagement in the horizontal upper legs of brackets 26. A coiled spring 28 encircles the pull-rod 22 and thus tends to keep the rollers in their uppermost position and projecting well through 95 platform 8. But when occasion requires, the operator may pull down on handle 23 and thus bring the top of rollers 18 flush with the top of platform 8. During that downward movement, the rollers and their supporting mechanism are guided in brackets 26 by ears 29 (Figs. 2 and 3) integral with the U-shaped plate 21 and adapted to rub at 100 their edges along the inner faces of brackets 26. Freedom of movement along slots 19 is 105 of advantage in adapting the machine to envelopes of different sizes and the bolts which connect the transverse bars 27 with the horizontal upper legs of brackets 26 are not screwed up so tight but that the operator 110 can move the mechanism along slots 19 as the occasion may require.

If no anti-friction rollers were used and the stacked envelopes were permitted to lie flat on table 8, the frictional engagement 115 of the lowermost envelope with the table top would be greater than is desired. It is the primary function of rollers 18 to reduce friction at this point. There is, however, much convenience and some operative advantage in having the rollers so supported by a spring that they will be depressed when a full stack of envelopes is placed over them. Except for this, there would be danger that one or more of the top en- 120 125 130

velopes might slide down between the stack and baffle plate 45 and there impede free passage of some of the envelopes over the drum 30. As soon as the operator completes 5 the work of stacking the envelopes on the platform, rollers 18 move upward to produce a tilting of the stack, thus placing the envelopes in such an inclined position as will facilitate entrance over drum 30.

10 When the envelopes are stacked for insertion into the machine, the flaps are adjusted at right angles to the bodies, as indicated in Figs. 1 and 3. The lowermost envelope is brought into proper alignment with the 15 rolls when the envelopes are placed on the receiving platform and spring-pressed vertical plate 11 is relied on to force the stack over progressively so that the lowermost envelope will, at all times, be in proper 20 alignment.

The feeding rolls (Figs. 1, 2, 6 to 8, 9 and 10).

The lowermost envelope from the stack 25 is gripped between the large feeding roll or drum 30 and a small upper roll 31. Feeding roll 30 has a pair of annular recesses in its working face in each of which is secured a rubber tread 32 with corrugated or knurled faces as shown in Fig. 7. This drum 30 is mounted on a drive shaft 33 to which it is locked by a set screw 34 (Fig. 6). Shaft 33 passes through hub 5 in which is an anti-friction wood lining 35 30 so constituted as not to require application of lubricating oil.

Roll 31 has a smooth yielding face of rubber or like material and does not rotate from frictional engagement with an envelope passed between it and drum 30, but, 40 on the contrary acts as a restraining baffle for all but the lowermost envelope and at the same time presents a yielding surface along which the envelope can be dragged by 45 the rubber surfaces of drum 30. Platform 8 is provided with a pair of longitudinal slots 37 and 38 (Fig. 2) through which the rubber treads of drum 30 project slightly. Roll 31 is positioned midway between these 50 two slots, as appears from Fig. 6, and thus contacts with that part of the envelope which bridges a gap between the rubber treads 32.

The smooth yielding rubber face of roll 55 31 is subject to considerable wearing action from envelopes sliding under the roll and provision has been made for turning roll 31 with an intermittent movement to equalize the wear on its face, as hereinafter described. Roll 31 is so mounted as to be capable of various other adjustments.

Cover plate 14, at its right hand end, is pierced by three bolts 39, 40 and 41. (Fig. 9.) Bolt 39 passes through a longitudinal slot in the horizontal leg of a bracket

42. The other or outer leg of this bracket is turned upwardly. Similarly bolts 40 and 41 pass through longitudinal slots in the horizontal leg of a wide bracket 43, the other or outer leg of which is turned upwardly. Secured to these outwardly turned legs of the two brackets by bolts 44 is a baffle plate 45 (Figs. 6 and 8), one function of which is to keep the stack of envelopes from crowding forward against roll 31. Lying against the rear face of baffle plate 45 and guided along its edges by the adjacent up-turned edges of brackets 42 and 43 is a vertically movable plate 46, the upper end of which is bent over as shown in Fig. 11 to engage with a keeper 47 on the lower end of a threaded shaft 48 which passes with threaded engagement through an ear integral with baffle plate 45, and is provided at its upper end with a knob 49. (Fig. 6.) By turning this knob, plate 46 can be made to slide in its guideway. Near the lower end of the plate 46 are two integral ears 50 which are bent forward to serve as supports for a shaft 51 (Figs. 8 and 10). Shaft 51 serves as a pivot for a pair of side plates 52 joined together by an integral bar 53 and provided at their lower extremities with a shaft 54 on which roll 31 may turn. Wrapped around shaft 51 is a coiled wire spring 55, one end of which rests against plate 46, and the other end of which engages one of the side plates 52. This spring holds the roll to its work with a yielding pressure but will permit upward swinging movement of the roll above shaft 51 to accommodate envelopes differing slightly in thickness. This spring connection will take care of any change from a one-page letter to a two-page letter. When the envelopes are much thicker, as when containing circul 50 ars or pamphlets, manual adjustment can be made at knob 39 before commencing to pass the envelopes through the machine.

The mechanism whereby roll 31 is caused to turn with an intermittent movement to equalize the wear on its face includes a gag roller 56 preferably of soft rubber and floating between roll 31 and its cross-bar 53. The upward thrust on roll 31 produced by its frictional contact with the passing envelope is sufficient to compress slightly the rubber of gag roll 56 and the contacting rubber face of roll 31, so that when the envelope has passed through there will be a slight rebound of these rubber elements to an extent sufficient to turn roll 31 slightly in a direction opposite to that of the traveling envelope. Therefore, in a sense roll 31 may be regarded as a spring-pressed barrier, the wearing surface of which is periodically renewed. Roll 31 can, of course, be turned by hand in a counterclockwise direction as viewed in Fig. 11 to present a new wearing surface for contact with passing envelopes.

Ordinarily, however, the intermittent slow rotative movement above described will be entirely sufficient to equalize the wear. cross-bar 53, by its bearing against the lower 5 end of plate 46, acts as a stop to limit downward swing of roll 31.

*The moistening device and its fountain.
(Figs. 1, 3 to 6, 8, 9 and 10).*

10 At the right hand end of base 1, as seen in Fig. 1, are ears 57 and 58 for carrying rubber cushions 59, and tapped into those ears are bolts 60 and 61 under which is clamped a cross bar 62. Resting loosely on an upwardly bent portion of this bar is the foot 63 of an automatic water fountain. This fountain comprises a metal cup 64 with an air intake and overflow vent 65, this cup being threaded to one end of a horizontal feed 20 pipe 66. The mouth of the cup is lined with a soft rubber collar 67 within which is loosely but closely fitted the neck of an inverted glass water bottle 68. The mouth of the bottle is at a level just below the air intake 25 65. This fountain is of the constant level type for water can flow out of the glass receptacle only in proportion as air flows in and air is admitted or excluded in accordance with the level of the water in the lower 30 part of the cup, as will be well understood by those skilled in the art.

A soft rubber check valve 69 is inserted through the neck of the bottle into the position shown in Fig. 5. While the fountain 35 is in use, this check valve rests on a leg 70 integral with the fountain cup and its leg 63, but when the water bottle is to be removed, the valve is released and seats against the neck of the bottle to prevent spilling any residue of water while lifting the bottle out for refilling.

To refill the bottle after removing it from the fountain the operator withdraws the soft rubber check valve 69 as if it were a cork 40 thus leaving the neck of the bottle unobstructed for filling. The valve is then pushed back into the bottle, and it makes no difference which end is inserted for both ends are alike. The cross section of the stem is such as to allow ample space for the passage of air upward and the passage of water downward.

The moistening device, together with the fountain, are easily removable from the machine for purposes of adjustment, cleaning, etc. To insure ease of removal, these elements are fastened to sub-base 3 by a single bolt 71 which passes through a lug 72 integral with the casting 73 which serves as a well for the moistening water and as a support for various other elements. Feed pipe 66 is threaded into a casting 73. Along the bottom edge of casting 73 are two lugs 74 and 75 bevelled to engage with the in-

clined front edge of a pair of lugs 76 integral with sub-base 3 (Fig. 3). The tightening of bolt 71 brings these inclined faces into wedging engagement and insures accurate alignment of all of the parts associated with casting 73.

70 A sheet metal box 77 with a detachable cover 78 encloses the moving elements of the moistening device.

The moving elements of the moistening device include an intermittently rotating sheet metal drum 79 within the flanged periphery of which is secured an annular brush 80 with outwardly projecting bristles. This drum turns slowly with an intermittent movement to moisten the bristles by progressive submergence of them in the water of the well 73, but with opportunity for the bristles to drain before being brought into contact with the gummed flaps of envelopes to be sealed.

75 Drum 79 is secured by a nut 81 to a threaded bushing 82, which is mounted on a bolt 83 on which it can freely turn. Bolted to drum 79 is a sheet metal drum 84 with a flange at its outer edge against which bears a frictional ratcheting device now to be described.

80 The frictional ratcheting device whereby the moistening brush is given an intermittent rotary movement comprises a dog 85 (Fig. 10) pivoted at 86 to the upper end of an oscillating arm 87. That arm is mounted on bushing 82 (Fig. 8) and is free to swing thereon. Integral with dog 85 is a weight 88, the lower edge of which is kerfed to form a tongue 89 which is bent at right angles to the weight so that it can strike against the edge of bar 87 and thus serve to keep the dog in convenient position for reassembly in case the mechanism is 85 taken apart for cleaning.

90 At 86 (Fig. 6) is a stub shaft on which dog 85 can swing, this shaft being threaded through arm 87 and secured by a nut 90. Beyond the threaded portion of the stub shaft is a cylindrical portion 91 (Figs. 6 and 9) which serves as a pin for engagement with a slot 92 in the upper end of a pivotally mounted oscillating lever 93. This lever 93 is free to swing about a stub shaft 94 supported by box 77 and equipped with a collar, a nut, and a lock nut as shown in Fig. 6. The oscillating movement is imparted to lever 93 by means of a cam 95 which is straddled by the bifurcated lower end of lever 93.

95 This cam is eccentrically mounted and is free to rotate on the reduced cylindrical end 96 of bolt 83. A bushing 97 is threaded to that bolt and is externally threaded to receive a nut 98, the function of which is to grip the wall of box 77 and hold bolt 83 and its associated parts in proper working 100 relation.

A simple form of clutch serves to establish driving connection between the main driving shaft 33 (Fig. 6) and the eccentric cam 95. This clutch consists of a pin 99 projecting at 5 the end of the hub of the drum 30 and adapted by rotary movement to strike against a similar pin 100 projecting from the side face of cam 95. A gag roller 79 holds drum 79 against rotation in reverse 10 direction.

The front wall of box 77 extends slightly about the axis of bolt 83 but is provided with an upwardly extending ear 101 through 15 which passes a bolt 102 to secure the box to the front apron 15 and give support thereto.

When an envelope is passed over drum 30 its depending gummed flap wipes across the damp bristles of the annular brush 80 and 20 the envelope then is pulled forward by the transfer rolls and ultimately is sealed at the next pair of rolls. The bristles of the brush are kept in a properly moistened condition by periodic submergence in the water of 25 the well 73 and the intermittent rotary movement of the brush is slow enough to protect against too much moisture in the bristles across which the envelope is wiped.

When the machine is started up in the 30 morning after it has been standing over night the bristles at the top of the drum will have dried out to such an extent as to be ineffective. There are, however, finger holes in the drum 79 accessible from the front of 35 the machine so that the operator can turn the drum by hand to bring properly moistened bristles into active position preparatory to starting the machine. Except for this the first few envelopes passed through 40 the machine might not have their flaps sufficiently moistened.

The drive (Figs. 1, 2, 6, 12, 13, and 14).

The machine as a whole is driven by an 45 electric motor 282 (Fig. 1) with its base 283 bolted to a transverse cross bar 284 bolted to base 1, as shown. The drive is through a round belt 285 to speed-reducing 50 pulleys 286 and 287. The latter is connected by a belt 289 to a pulley 288 (Fig. 6). Pulley 288 is secured to drive shaft 33 by a set screw 290. Integral with pulley 288 is a larger pulley 291 having a belt 292 passing 55 to a pulley 293 (Fig. 2) which is formed integral with a cylindrical sleeve 294 carried at either end on anti-friction wooden bearing sleeves.

To operate the machine, the addressed and 60 filled envelopes are placed horizontally in a stack on the receiving platform, with their gummed flaps hanging down in shingled relation to one another and their stamped ends toward drum 30. The lowermost envelope 65 of the stack is caught between the

feed rollers and pulled out from beneath the stack and advanced across the laterally projecting moist bristles of the moistening brush. The upper retarding or separating roller meantime acts as a guard or barrier to prevent advancement of other envelopes 70 of the stack. The moistened envelope passes directly forward through the transfer rolls while its downwardly hanging flap strikes against an inclined plate and is gradually 75 folded upward against the horizontal body of the envelope, so that when the envelope reaches the sealing rolls, the flap can be squeezed tightly against the envelope. The sealed envelope then passes to the printing 80 rolls where the postage stamp is cancelled and the name of the post office and the date and hour and the user's permit number are printed adjacent to the canceled stamp, as described in my copending application, 85 Serial No. 112,487 filed May 29, 1926.

A great variety of changes may be made in details of the structure and in the mode of operation of the several parts without departing from the spirit of the invention as 90 defined by the appended claims.

I claim:

1. In a machine of the character described, the combination of a platform on which a stack of envelopes may be placed with their 95 bodies substantially horizontal and their flaps hanging downward over the edge thereof in shingled relation, a feeding drum for withdrawing the lowermost envelope, and means for reducing the friction of that envelope on said platform.

2. In a machine of the character described, the combination of a platform on which a stack of envelopes may be placed with their 100 bodies substantially horizontal and their flaps hanging downward over the edge thereof in shingled relation, a feeding drum for withdrawing the lowermost envelope, and a pair of rollers for reducing the friction of 105 that envelope on said platform.

3. In a machine of the character described, the combination of a platform on which a stack of envelopes may be placed with their 110 bodies substantially horizontal and their flaps hanging downward over the edge thereof in shingled relation, a feeding drum for withdrawing the lowermost envelope, a roller for reducing the friction of said envelope on said platform, and a spring for 115 lifting said roller to tilt the stack of envelopes, substantially as described.

4. In a machine of the character described, the combination of a platform on which a stack of envelopes may be placed with their 120 bodies substantially horizontal and their flaps hanging downward over the edge thereof in shingled relation, a feeding drum for withdrawing the lowermost envelope, a pair of rollers on which said stack of 125 envelopes rest, a spring for lifting said envelope, and a roller for reducing the friction of said envelope on said platform.

rollers to facilitate delivery to said feeding drum, and manually operable means for lowering said rollers at will.

5. In a machine of the character described, the combination of a platform on which a stack of envelopes may be placed with their bodies substantially horizontal and their flaps hanging downward over the edge thereof in shingled relation, a feeding drum for withdrawing the lowermost envelope, and a pair of rollers contacting with the lowermost envelope of the stack, said rollers being adjustable along said platform to better accommodate envelopes of different lengths.

6. In a machine of the character described, the combination of a platform on which a stack of envelopes may be placed with their bodies substantially horizontal and their flaps hanging downward over the edge thereof in shingled relation, a feeding drum for withdrawing the lowermost envelope, a pair of rollers contacting with the lowermost envelope of the stack, said rollers being adjustable along said platform to better accommodate envelopes of different lengths, a spring for lifting said rollers to tilt the stack of envelopes, and manually operable means for compressing said spring and thereby lowering said rollers at will.

7. In a machine of the character described, the combination of a platform on which a stack of envelopes may be placed with their bodies substantially horizontal and their flaps hanging downward in shingled relation at the side of said platform, a feeding drum for withdrawing the lowermost envelope of the stack and a cylindrical baffle under which said envelope is drawn by said drum.

8. In a machine of the character described, the combination of a platform on which a stack of envelopes may be placed with their bodies substantially horizontal and their flaps hanging downward in shingled relation at the side of said platform, a feeding drum for withdrawing the lowermost envelope of the stack, said feeding drum having a pair of rubber treads spaced apart, and a cylindrical baffle under which said envelope is drawn by said treads, said baffle remaining substantially stationary during transit of the envelope and engaging that part of the envelope which bridges the space between said treads.

9. In a machine of the character described, the combination of a platform on which a stack of envelopes may be placed with their bodies substantially horizontal and their flaps hanging downward in shingled relation at the side of said platform, a feeding drum for withdrawing the lowermost envelope of the stack, and a cylindrical baffle under which said envelope is drawn by said

drum, said baffle moving but slightly during transit of said envelope and having a smooth surface for engagement with the envelope.

10. In a machine of the character described, the combination of a platform on which a stack of envelopes may be placed with their bodies substantially horizontal and their flaps hanging downward in shingled relation at the side of said platform, a feeding drum having rubber treads spaced apart and adapted to contact with the lowermost envelope of the stack and a cylindrical baffle having a smooth surface yieldingly engaging that part of the envelope which bridges the space between said treads.

11. In a machine of the character described, the combination of a platform on which a stack of envelopes may be placed with their bodies substantially horizontal and their flaps hanging downward in shingled relation at the side of said platform, a feeding drum for withdrawing the lowermost envelope of the stack, and a cylindrical baffle yieldingly engaging the upper face of said envelope said baffle being restrained against free movement therewith.

12. In a machine of the character described, the combination of a platform on which a stack of envelopes may be placed with their bodies substantially horizontal and their flaps hanging downward in shingled relation at the side of said platform, a feeding drum for withdrawing the lowermost envelope of the stack, and a spring pressed cylindrical baffle under which said envelope is drawn by said drum.

13. In a platform of the character described, the combination of a platform on which a stack of envelopes may be placed with their bodies substantially horizontal and their flaps hanging downward in shingled relation at the side of said platform, a feeding drum for withdrawing the lowermost envelope of the stack, and a spring pressed cylindrical baffle under which said envelope is drawn by said drum, said baffle being restricted against free rotation with the travelling envelope, but being free to turn in the opposite direction.

14. In a platform of the character described, the combination of a platform on which a stack of envelopes may be placed with their bodies substantially horizontal and their flaps hanging downward in shingled relation at the side of said platform, a feeding drum for withdrawing the lowermost envelope of the stack, a spring pressed cylindrical baffle under which said envelope is drawn by said drum, and a gag roller restraining said baffle against free rotation with the travelling envelope.

15. In a machine of the character described, the combination of a receiving plat-

form on which a stack of envelopes may be placed, a continuously rotating feeding drum for withdrawing an envelope from the stack, a cylindrical baffle across the face of which 5 said envelope is drawn by said drum, and means for intermittently turning said cylindrical baffle to equalize the wear on the working face thereof.

16. In a machine of the character described, the combination of a receiving platform on which a stack of envelopes may be placed, a continuously rotating feeding drum for withdrawing an envelope from said stack, a cylindrical baffle across the face of which 10 said envelope is drawn by said drum, and means restraining said baffle against movement with the passing envelope, but rotating the said baffle in the reverse direction with an intermittent movement after the envelope 15 has passed.

17. In a machine of the character described, the combination of a receiving platform on which a stack of envelopes may be placed, a feeding drum for withdrawing an envelope from the stack a cylindrical baffle 20 across the face of which said envelope is drawn by said drum, and spring pressed means for permitting said baffle to swing away from said drum when envelopes of 25 greater thickness are to be handled.

18. In a machine of the character described, the combination of a receiving platform on which a stack of envelopes may be placed, a feeding drum for withdrawing an envelope from the stack, a cylindrical baffle 30 coacting with said drum and across the face of which said envelope is drawn by said drum, a swinging support for said baffle permitting movement thereof to accommodate envelopes of varying thickness and a stop on said frame limiting movement of said baffle away from said drum.

19. In a machine of the character described, the combination of a receiving platform on which a stack of envelopes may be placed, a feeding drum for withdrawing an envelope from the stack, a cylindrical baffle 45 coacting with said drum and across the face of which said envelope is drawn by said drum, a swinging support for said baffle permitting movement thereof to accommodate envelopes of varying thickness and a stop on said frame limiting movement of said baffle away from said drum, and a spring coacting 50 with said frame to return the baffle toward said drum.

20. In a machine of the character described, the combination of a receiving platform on which a stack of envelopes may be placed, a feeding drum for withdrawing an envelope from the stack, a cylindrical baffle, a frame supporting said baffle, a pivot 60 on which said frame may swing, and means for adjusting said pivot toward or away from said drum to adjust the effective gap

between said baffle and said drum, in accordance with the thickness of the envelopes to be handled.

21. In a machine of the character described, the combination of a receiving platform on which a stack of envelopes may be placed, a feeding drum for withdrawing an envelope from the stack, a cylindrical baffle, a frame supporting said baffle, a pivot 70 on which said frame may swing, and means for adjusting said pivot toward or away from said drum to adjust the effective gap between said baffle and said drum, in accordance with the thickness of the envelopes to be handled, a stop for limiting the swing 75 of said baffle away from said drum and a spring operatively connected to return said baffle toward said drum.

22. In a machine of the character described, the combination of a platform on which a stack of envelopes may be placed with their bodies substantially horizontal and their flaps hanging downward in shingled relation at the side of said platform, a feeding drum for withdrawing the lowermost envelope of the stack, and a spring-pressed plate for progressively pushing said envelopes laterally into proper alignment with said feeding drum.

23. In a machine of the character described, the combination of a platform on which a stack of envelopes may be placed with their bodies substantially horizontal and their flaps hanging downward in shingled relation at the side of said platform, spring pressed rollers at one end of the platform and on which said stack of envelopes rest, a feeding drum at the other end of said platform for withdrawing the lowermost envelope of the stack, and a spring-pressed plate for progressively pushing said stack of envelopes laterally so that at all times the lowermost envelope will be in operative alignment with said feeding drum.

24. In a machine of the character described, the combination of a platform on which a stack of envelopes may be placed with their bodies substantially horizontal and their flaps hanging downward in shingled relation at the side of said platform, a feeding drum for withdrawing the lowermost envelope of the stack, rollers on which said stack of envelopes rest, a spring pressed plate for holding the lowermost envelope in operative alignment with the feeding drum, a stationary baffle at the front of said stack, and a cylindrical baffle across the face of which the envelopes are drawn in succession by said feeding drum.

25. In a machine of the character described, the combination of a platform on which a stack of envelopes may be placed with their bodies substantially horizontal and their flaps hanging downward in shingled relation at the side of said plat-

form, a feeding drum for withdrawing the lowermost envelope of the stack, rollers on which said stack of envelopes rest, a spring-pressed plate for holding the lowermost envelope in operative alignment with the feeding drum, a stationary baffle at the front of said stack, and a cylindrical baffle across the face of which the envelopes are drawn

in succession by said feeding drum, said cylindrical baffle being restrained against rotation with a passing envelope but being free to turn in the reverse direction after the envelope has passed. 10

In testimony whereof I affix my signature.

JOHN W. ESKHOLME.
